UNITED STATES PATENT OFFICE.

WILLIAM L. CUMMINGS, OF LANSDOWNE, PENNSYLVANIA.

RADIUM NEEDLE.

Application filed May 10, 1921. Serial No. 468,309.

To all whom it may concern:

Be it known that I, WILLIAM L. CUMMINGS, a citizen of the United States, residing at Lansdowne, in the county of Delaware and State of Pennsylvania, have invented certain new and useful Improvements in Radium Needles, of which the following is a specification.

One object of my invention is to provide an improved radium needle for enclosing radium salt and radium emanation tubes, which has the advantages of detachable and interchangeable points, eyelet and handle.

Another object is to provide such needles with radium barrels so constructed that if desired two or more barrels can be readily connected together in a single needle.

A further object of my invention is to provide a radium needle which can be used with advantage and convenience in numerous capacities.

These objects, and other advantageous ends which will be described hereinafter, I attain in the following manner, reference being had to the accompanying drawings in which

Figure 1 is an enlarged view of a needle constructed in accordance with my invention with the handle, point, and single radium barrel connected ready for use,

Figure 2 is an enlarged view of the needle with an eyelet substituted for the handle shown in Figure 1; the construction being shown as to readily permit the interchange of the handle and eyelet,

Figure 3 is a view of the same general character as shown in Figure 2 with two radium barrels connected together in axial alignment,

Figure 4 is an enlarged detail view of the handle,

Figure 5 is an enlarged detail view of the body portion of the barrel,

Figure 6 is a detail view of the barrel closing and coupling member,

Figures 7 and 8 are detail views of two different forms of needle points which I preferably employ,

Figure 9 is a detail view of the eyelet,

Figure 10 is a longitudinal section, greatly enlarged, of the body portion of the radium barrel illustrating the same before said closing and coupling member is connected therewith, and

Figure 11 is a view of the same general

character as shown in Figure 10 with said closing and coupling member connected to the body portion of the barrel.

The parts of my improved radium needle are preferably constructed of non-corrosive acid-resistant metal which has the strength of steel such for example as "monel."

Referring to the drawings, my improved needle includes a barrel 12 adapted to contain radium, the parts of which are shown in Figures 5 and 6 and also in Figures 10 and 11. The barrel 12 includes an elongated body portion 13 providing a cavity 14 in which can be placed the radium element; said cavity being located entirely between the opposite end portions 15 and 16. The end portion 16 has a screw threaded hole 17 extending axially and communicating with the cavity 14 at one end thereof and the radium element can be inserted in the cavity through the hole 17. A barrel closing and coupling member 18 has a central portion 19 with two oppositely disposed stems 20 and 21; said central portion being of larger diameter than the stems 20 and 21 so as to provide shoulders 22 and 23. The stems 20 and 21 are screw threaded and after the radium element has been inserted in the cavity 14 of the barrel body portion 13, the stem 20 of the barrel closing and coupling member 18 is screwed in the hole 17 of said body portion so that the shoulder 22 abuts the extreme end 24 of the body portion, after which the member 18 is soldered to the body portion 13, at the parting between the central portion 19 of the member 18 and the end 24 of the body portion 13 so as to hermetically seal the radium element within the cavity 14. The central portion 19 of the member 18 is preferably made of the same outside diameter as the diameter of the body portion 13 so that when the member 18 is connected to the body portion 13 to produce the barrel 12, as shown in Figure 3, the outer surfaces of the body portion and member 18 will be flush.

The opposite end portion 15 of the body portion 13 has an axially extending screw threaded hole 25 in which may be screwed either the screw threaded stem 26 of the elongated handle 27 or the screw threaded stem 28 of the eyelet 29. The stem 21 of the member 18 serves for the attachment of points such for example as shown in detail

in Figures 7 and 8; said points having screw threaded holes 30 in which the screw threaded stem 21 of the member 18 can fit. If desired two or more of the radium barrels can be connected together in axial alignment as shown in Figure 3; the stem 21 of one barrel being screwed into the hole 25 of the other barrel as is obvious from the construction shown in Figure 11.

10 In the use of my invention when it is desired to use the needle in a cancer that is exposed and easily accessible, the eyelet is screwed onto the barrel as shown for example in Figure 2 and the eyelet can be employed for drawing a thread and also for the security of the needle and for removing the same from the condition being treated. To illustrate this manner of use in the treatment of a cancer of the bladder where an opening has been made and the growth exposed, the needles are inserted into the growth. After the needles are inserted, the wound is sewed up and the needles withdrawn by the threads through the usual 25 drainage tube.

In the treatment of cancer of the prostate the needle is used as shown in Figure 1 with the handle attached, by a perineal puncture.

In the event it is desired to use the needles 30 in treatment of cavities and not for insertion purposes the points and eyelets or handles may be detached and the barrels enclosed in a brass tube similar to that used when the radium salt is sealed in the usual glass 35 capsules, and then inserted in one of these brass tubes.

Thus my invention has a wide range of use since it has the advantages of using the radium as a needle and at the same time the 40 radium can be used in tubular form in the event the condition to be treated warrants the radium in this form.

Inasmuch as the effectiveness of the rays from radium is in proportion to the distance 45 between the source of the rays and the condition to be rayed, it is apparent that radium in the needle form is more effective than when used in tubular form and applied to the condition.

50 Considering that one of the barrels contains approximately 12½ milligrams of radium element, by combining two of these needles it is possible in one continuous needle to have 25 milligrams of radium element. In some conditions this is the dosage required whereas if 37½ milligrams of radium element is desired as the dosage the same can be had by combining three of the barrels; assuming that the condition is one 55 favorable for the use of the radium in this manner.

Furthermore the construction as above described and as illustrated permits the quick

interchange of parts either to substitute the handle for the eyelet or vice versa or for 65 using one or more of the barrels for varying the amount of radium required.

While I have described my invention as taking a particular form, it will be understood that the various parts of my invention 70 may be changed without departing from the spirit thereof, and hence I do not limit myself to the precise construction set forth, but consider that I am at liberty to make such changes and alterations as fairly come with 75 in the scope of the appended claims.

Having thus described my invention, what I claim as new and desire to secure by Letters Patent is:—

1. A radium needle including a barrel 80 adapted to contain radium having a screw threaded stem projecting from one end and a screw threaded hole at the opposite end whereby implements and accessories of different kinds may be attached to opposite 85 ends; substantially as described.

2. A radium needle including a barrel having a body portion providing a cavity adapted to contain radium and a screw threaded hole communicating with said 90 cavity; and a closing and coupling member having opposed screw threaded stems, one of which is adapted to be screwed into said hole of the body portion, the other serving as means for attachment of another part; 95 substantially as described.

3. A radium needle including a barrel having a body portion providing a cavity adapted to contain radium and a screw threaded hole communicating with said 100 cavity; and a closing and coupling member having opposed screw threaded stems, one of which is adapted to be screwed into said hole of the body portion, the other serving as means for attachment of another part, 105 substantially as described.

4. A radium needle including a barrel having a body portion providing a cavity 110 adapted to contain radium and a screw threaded hole communicating with said cavity; and a closing member having a screw threaded hole and another portion abutting the body 115 portion adjacent the outer end of said hole, said member being in sealed connection with said body portion; substantially as described.

In testimony whereof I have signed my 120 name to this specification in the presence of two subscribing witnesses.

WILLIAM L. CUMMINGS.
